4 Claims. (Cl. 102—49)

1

The body of a projectile may be manufactured in various ways, and in particular from a forged bar, or by moulding (semisteel), which is the most common method or again by shrinking a steel tube.

In the first case, it is possible to obtain a blank which is closed at the rear, which has the advantage of being absolutely fluid-tight, whereas in the second case, as the blank is open at both ends, it is necessary to fit ends thereto by any method. On the other hand, the main advantage obtained by the use of a tube is a considerable saving of material, which may be as much as 20 to 25%, as a result of the reduction of waste in machining; furthermore, the rate of manufacture may be much faster.

Although the use of tubes is suitable in particular for the manufacture of hand-grenades and aerial bombs, it is quite the contrary when it is required to manufacture projectiles which are intended to be fired from a gun. As such projectiles are subjected, when firing, to the action of the propelling gases, it is necessary for their case to be absolutely fluid-tight at the rear; the slightest leak due to a hidden fault of manufacture might, in fact, be sufficient to cause serious accidents when they are being fired. This is the reason why, in the manufacture of artillery projectiles, it is preferred in general to renounce the advantages that may be obtained by the use of tubes and to adhere to the old method consisting in using a body manufactured from a bar and completely closed at the rear.

As the casing of projectiles equipped with fins, which are intended to be fired by mortars, only have to support a moderate force when the shot is fired, it should be made as light as possible, and it would be a great advantage in this case to be able to manufacture it from a tubular blank, the only problem to be solved, which has not yet been solved in a satisfactory manner, being that of the fluid-tightness at the rear.

The present invention is intended to fill this need. It relates to a projectile equipped with fins, the body of which is provided with a screw-threaded rear orifice, into which is screwed a nipple which is secured, at any rate after mounting, to a tail supporting the fins, said projectile being remarkable in particular in that the connection between said tail and the body of the projectile is provided with a metalloplastic deformable fluid-tight joint mounted in an annular housing provided in the body of the projectile, said joint being deformed by compression in its housing by a circular shoulder of the nipple when

same is screwed into the body of the projectile.

The fact that this fluid-tight joint is deformable by the action of screwing the nipple has the effect that, after said nipple is mounted, the joint completely fills its housing and thus makes the rear of the projectile fluid-tight.

According to another characteristic of the invention, the fluid-tight joint is provided with a malleable metal sheath, which is open circularly on one side and contains a plastic material. This arrangement enables the sheath to become deformed without crumpling and without its edges overlapping one another when the plastic material is compressed.

15 Since the time taken by the projectile to travel through the barrel of a mortar is very short, the joint is only slightly heated and may very well be made, internally, of cardboard.

When the joint is compressed, it first undergoes a considerable deformation which is permanent and irreversible, owing to the crushing of the plastic material which has no natural rigidity, the metal sheath only offering a slight resistance to this deformation owing to its annular 20 shape which enables it to undergo larger deformations by the action of small forces.

At the end of this period of compression, the joint has assumed substantially the shape of its housing, save in the corners of same, where there 25 remains a small space of approximately triangular cross-section.

If the compression of the joint is continued, the pressure caused by the resistance to crushing offered by said joint quickly increases and offers 30 more and more resistance to further deformations. As the plastic material is thus solely in compression, it acquires a certain resilience.

There is therefore during the first period of 35 the compression, plastic and permanent deformation of the joint by a slight pressure which slowly increases, whereas during the second period which is shorter, the joint is resiliently deformed, i. e. in a reversible manner, by a larger force which 40 quickly increases with the compression path.

45 In order that the joint shall provide fluid-tightness it is necessary for it to exert on the walls of its housing a sufficient pressure to counterbalance that of the gases, which is only possible if 50 said joint is in the region of resilient deformations, i. e. the second part of the compression path.

Fluid-tightness will be more efficient as the pressure exerted by the joint on the walls is 55 greater, and the fluid-tightness will only be per-

fect so long as the screwing travel of the nipple is only limited by the compression of the joint.

The metal sheath is preferably given a rectangular cross-section with rounded corners, whereas its housing in the projectile is of purely rectangular cross-section.

The joint is thus prevented, as it is deformed by the pressure of the screw when the nipple is being tightened from being pinched and producing a jamming which would make it impossible to screw the nipple right home; on the contrary, it only more completely fills the space provided for its fluid-tight functions. Furthermore, the presence of the rounded corners of the sheath has the effect of providing small expansion spaces for the gases.

In a particular embodiment of the invention, the portion which forms a nipple and which is adapted to engage in the rear orifice of the projectile body is provided with two ground cylindrical bearing surfaces of different diameters, which are axially stepped and respectively engage in corresponding circular recesses provided at the rear of said projectile body, the housing for the fluid-tight joint being formed by the recess of large diameter.

This makes it possible to obtain a perfectly guided sliding device which, at the end of its travel, locks the fluid-tight joint absolutely accurately in its housing. The length of the small diameter bearing surface is such that the same begins to engage in its recess before the fluid-tight joint begins to be compressed in its housing, whereby said joint is prevented from being driven back and jammed when the nipple is being screwed tight.

The use of these two ground bearing surfaces furthermore has the advantage of effecting a suitable centring of the fins on the axis of the projectile, which is very important for the accuracy of firing. The same result cannot be obtained when, as is generally the case, the tail is only provided with a simple screw-threaded nipple adapted to screw in a blind hole bored in the end of the projectile.

For the purpose of breaking the jet of gases by expansion, and of preventing it from propagating inside the joint, according to a further characteristic of the invention, a circular expansion groove is provided on the periphery of the large diameter ground bearing surface.

The tail of the projectile may advantageously be manufactured of preferably untreated drawn steel tube, instead of using a tail which is machined from a bar; a saving of material and an economy of manufacture is obtained thereby. In this case, the coupling between the tail and the body of the projectile comprises a separate part forming a connection which is screwed right home in the projectile, a second screw-thread provided on said connection serves for screwing on to the tail. This connecting member being of small size can be mass produced with the greatest accuracy, which is an advantage when it comprises ground cylindrical portions, the accuracy of which is an important matter.

Additional fluid-tightness is given to the device by varnishing the whole of the above described connection when mounting it. Finally, a layer of pitch cement may provide a final means for preventing the gases from passing.

Other peculiarities of the projectile according to the invention will become apparent from the ensuing description.

In the accompanying drawing:

Fig. 1 is a general view, in axial section, of a projectile equipped with fins according to the invention and provided with a tubular tail and a connecting member.

5 Fig. 2 shows, likewise in axial section, the detail of the fluid-tight coupling, before compression of the fluid-tight joint by the connecting member.

Fig. 3 shows the fluid-tight joint on a larger scale.

10 Fig. 4 shows the same detail as Figs. 2 and 3, after compression and deformation of the fluid-tight joint and the tail being screwed right home.

Fig. 5 is a general view, in axial section, of a projectile equipped with fins according to the invention, provided with a tail which has been machined from a bar with its nipple.

Fig. 6 shows, in partial axial section, the detail of the fluid-tight coupling, after screwing the tail (Fig. 5) on the projectile.

20 The projectile shown in Fig. 1 comprises a tapered body 1 and a cartridge-holder tail 2 provided with fins 3; said tail is adapted to screw on the rear of the projectile body 1; in the example described, it is a perforated tail of known type, made from a drawn steel tube; an intermediate member or nipple 4, which is adapted to screw,

25 on the one hand in the front part of said tail 2, and on the other hand in the rear part of the projectile body 1, acts as a connection between the tail and the projectile body. It is obvious

30 that as shown in Figs. 5 and 6, the tail could also be of any type, machined from a bar and having at the end thereof a screw-threaded nipple.

The body 1 of the projectile is made from a tube section. Consequently it has, after shrinking and machining the front and rear ogival portions, a front orifice 5 and a rear orifice 6; said orifice 6 is tapped at 7 so that the connection 4, which forms a nipple, can be screwed therein.

35 40 The tubular tail 2, for its part, is tapped at 8 at its front part in order to enable the connection 4 to be screwed.

A deformable joint 9 forms a seal for the propelling gases between the connection 4 and the body 1.

45 The projectile body 1 has, at the rear part thereof, two stepped concentric circular recesses: the large diameter recess 10 is comparatively deep and serves as a housing for the sealing joint 9 (Fig. 2); the inner recess 11 is shorter.

The connection 4 is screw-threaded at both ends at 8' and 7' so that it can screw, on the one hand into the tail 2, and on the other hand into the rear orifice 6 of the body 1 which it completely closes; said connection is such that it can be screwed right home in the body of the projectile with a screwing torque which is calculated proportionally to the capacity of deformation of the joint 9 and to the axial travel of the connection 4 when it is being screwed into the body 1, and also to the strength of the thread 7' and the pressure of use and of reception.

50 55 60 65 The connection 4 is provided with two accurately machined cylindrical bearing surfaces 12 and 13, the respective diameters of which correspond, with a very slight play, to the diameters of the two recesses 10 and 11. Said bearing surfaces serve in the first place for guiding and centring the connection 4, and consequently the tail 2 when it is being mounted, which is very important in order that the fins shall be accurately in the axis.

70 75 76 The large diameter bearing surface 12 moves like a piston inside the recess 10 which acts as a cylinder.

The small diameter bearing surface 13 penetrates inside the recess 11 and separates the fluid-tight joint 9 from the screw-thread 7 and makes it possible to prevent said joint from jamming in the screw while it is being tightened, which might cause it to lock; it is long enough to penetrate into its housing 11 before the joint 9 begins to be compressed (Fig. 2).

The housing of the fluid-tight joint 9 is bounded, in the radial direction, by the inner face 14 (Fig. 3) of the recess 10 and by the periphery 15 of the bearing surface 13, and in the axial direction, by the end 16 of the recess 10 and by the annular face 17 between the bearing surfaces 12 and 13.

When the connection 4 is screwed into the rear orifice 6 of the projectile body 1, the fluid-tight joint 9 is compressed more and more between the face 17 and the end 16 of the recess 10 which serves as a housing therefor, until the fluid-tight joint 9, which is deformed by the pressure, completely fills its housing, without leaving the slightest possible leak (Fig. 4). The joint 9 being completely compressed, there remains a certain empty space between the front part 13' of the bearing surface 13 and the bottom 11' of the recess 11.

The fluid-tight joint 9 shown in Fig. 3 comprises a deformable metal sheath 20 which is circularly slit along one of its sides, at 21; said sheath contains a plastic material 22 such as cardboard. The existence of the rounded corners of the sheath 20 eliminates any risk of said sheath becoming pinched and jammed between the partitions of its housing while the tail is being screwed on, and little by little it assumes the final shape shown in Fig. 4 in which it completely fills its housing. It then only remains to screw the tail 2 on to the connection 4 until the face 18 comes into contact with the face 19 of the projectile; the tail thus acts as a lock-nut, and if the faces 18 and 19 have been carefully trued, the tail is perfectly centred on the projectile.

A circular expansion groove 23 (Fig. 2) provided on the periphery of the ground bearing surface 12 has the effect of breaking the jet of gases when the shot is fired and breaks its propagation in the direction of the fluid-tight joint 9. Said groove also has the advantage of decreasing the bearing surface 12 which is thus easier to construct.

The connecting member 4 is covered with a coat of varnish not shown in the drawing, and a mass of pitch cement 24 lodged in the end of the body 1 makes the rear part of the projectile still more fluid-tight.

In the embodiment shown in Figs. 5 and 6, the tail 2 and its nipple 25 are in one piece, being assumed to have been machined from a bar.

The details of the fluid-tight joint, the bearing surfaces of the nipple and their housings in the body of the projectile are the same as in the example of Figs. 1 to 4.

The only difference consists in the fact that, instead of first screwing home the connection in the projectile, in order to press the fluid-tight joint in its housing, the joint is compressed by means of the tail itself. The construction is simpler, but the mounting and the centring of the tail are not so accurate, since said tail can only be screwed until the joint 9 is completely compressed in its housing; a slight play must

therefore remain between the faces 18 and 19, and the tail cannot act as a lock-nut in the manner described in the example of Figs. 1 to 4.

It is obvious that the invention has only been illustrated and described by way of example and that, without exceeding its scope, many other embodiments could be constructed.

Having now described my invention, what I claim as new and desire to secure by Letters Patent is:

1. In a projectile equipped with fins, a hollow body provided at the rear with a tapped orifice followed in the outward direction and axially by a first cylindrical recess, then by a second rear one of larger diameter and connected at right angles to the former by a flat surface perpendicular to the longitudinal axis of said body, a nipple screwed in said tapped orifice and provided with two ground cylindrical bearing surfaces of different diameters, corresponding to the diameters of said recesses, said surfaces being axially stepped, connected by a flat surface perpendicular to the longitudinal axis of said nipple and respectively engaged in said recesses and the bearing surface engaged in the first cylindrical recess having an axial length greater than that of said recess so that an annular space of rectangular longitudinal radial section is left in said second rear recess by said nipple, a deformable metallo-plastic fluid-tight annular seal located in said annular space and compressed by said nipple between said flat surfaces, and a tail provided with fins and connected to said hollow body by means of said nipple.

2. A projectile equipped with fins according to claim 1, wherein the length of the small diameter bearing surface of said nipple is such that said bearing surface is already engaged in the corresponding recess of said hollow body before said fluid-tight joint begins to be compressed by said nipple.

3. A projectile equipped with fins according to claim 1, wherein a circular expansion groove is provided on the periphery of the large diameter ground bearing surface of said nipple.

4. A projectile equipped with fins according to claim 1, wherein said metallo-plastic annular seal comprises a malleable metal sheath, provided with a circular slit and having a longitudinal radial cross-section in the form of a horseshoe, the longitudinal axis of which is parallel to the longitudinal axis of said body, and a plastic material in contact with the flat surface of the rear recess of said body through said circular slit.
